UNITED STATES PATENT OFFICE

2,533,806

BOTTLE

Harry R. Holzapfel, Richmond, Ind.

Application July 6, 1949, Serial No. 103,261

1 Claim. (Cl. 215—6)

1

This invention relates to a bottle, and more particularly to a bottle for holding and dispensing two separate liquids.

The object of the invention is to provide a dispensing bottle which includes a pair of compartments for holding separate or different liquids, the bottle including means for consecutively dispensing the contents of said compartments.

Another object of the invention is to provide a bottle which is constructed so that two liquids can be stored therein without intermixing, and wherein a means is provided for separately dispensing the liquid.

A further object of the invention is to provide a bottle which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a vertical sectional view through the bottle, according to the present invention;

Figure 2 is a view similar to Figure 1, but showing the position of the parts of the bottle when the contents are being dispensed; and

Figure 3 is a fragmentary vertical sectional view of a modified dispensing bottle.

Referring in detail to the drawings, Figures 1 and 2, the numeral 10 designates a container which is fabricated of suitable material such as glass. The container 10 includes a sidewall 11 and a thick bottom wall 12. The container 10 further includes an open mouth 13 in its upper end, Figure 2, and arranged adjacent the open mouth 13 is a recess 14. The recess 14 defines a shoulder 15 adjacent the upper end of the container 10 for a purpose to be later described.

Arranged in the lower end of the container 10 is a sloping side wall which coacts with the bottom wall 12 to define a pyramidal compartment 17. The compartment 17 is provided with an open mouth 18 in the upper end (Figure 2).

The upper end of the wall 16 is enlarged and defines a lip 19. For closing the mouth 18 of the compartment 17, closure 21 is provided, the closure being fabricated of suitable material such as plastic or paper coated with wax. The closure 21 is provided with concave sides.

For lifting the closure 21 from the open mouth 18 as when the contents of the compartment 17 are to be dispensed, a cord or cable 23 of flexible material has one of its ends secured to the closure 21. The other end of the cord 23 passes up-

2

wardly through a cap 24 and is provided with a head 25 on its end so that the cord 23 will not accidentally work loose from the cap 24. The cap 24 normally closes the open mouth 13 of the container 10, and normally the cap 24 is seated in the recess 14, as shown in Figure 1. A tab 26 projects from the upper surface of the cap 24 and the tab 26 is adapted to be gripped between the user's fingers when the cap 24 is to be lifted out of the recess 14. The cord 23 is sufficiently long so that the cap 24 can be lifted out of the open mouth without lifting closure 21 off of the mouth 18 so that if desired, the contents of the container 10 can be dispensed through the open mouth 13 without dispensing the contents of the compartment 17.

A cover or cap 27, which may be made of metal, is normally crimped over the upper lip 28 of the container 10, as shown in Figure 1, for protecting the cap 24.

Referring to Figure 3, there is shown a slightly modified model which differs from the bottle of Figures 1 and 2 in that the side wall 11 of the outer container is indented as at 29 in order to provide a neater exterior appearance as well as provide a more comfortable and firmer grip for handling purposes. Otherwise, the use of the bottle of Figure 3 is the same as the bottle of Figures 1 and 2.

30 In use, liquid is placed in the compartment 17, and the closure 21 is positioned so that it closes the open mouth 18 as shown in Figure 1. Then, a separate or different liquid is placed in the container 10. It will be apparent that the closure or stopper 21 will prevent any intermixing of the liquid in the container 10 and the compartment 17. The cord 23 is then arranged as shown in Figure 1 and the cap 24 is positioned within the recess 14. Then, the cover or cap 27 is mounted 35 on the upper end of the container 10 and the bottle with the two different liquids therein can be stored until needed. To dispense the contents of the bottle, the reverse procedure is followed. Thus, the cover 27 is removed, and the cap 24 is 40 lifted out of the recess 14 by means of the tab 26. Then, the liquid in the container 10 can be dispensed out through the open mouth 13. When it is desired to empty the contents of the compartment 17, the closure 21 is lifted out of the 45 mouth 18 by means of the cord 23 and then the contents of the compartment 17 can be readily dispensed.

As previously stated, the cord 23 is slightly longer than the distance between the mouth 18 50 of the compartment 17 and the mouth 13 of the

container 10. This arrangement makes it possible to lift out the cap 24 by means of the tab 26 so that the contents of the container 10 can be dispensed without dispensing the contents of the compartment 17. The dispensing bottle of the present invention may be used for dispensing alcoholic or other beverages. Thus, the compartment 17 can be filled with whiskey and sealed by the closure 21 and the outer container 10 can be filled with soft drink or the like. These liquids can be dispensed as previously described.

What I claim:

A bottle having a body and neck, said neck having an inner annular shoulder located below its upper edge and having an outer bead for the reception of a cap, a disc resting on the shoulder and provided with an opening, a compartment within the lower portion of the body provided with an upwardly facing discharge opening, a closure for said discharge opening, and a flexible member terminally attached to the disc and closure and passing freely through the opening in the disc, said member providing means by which the closure may be removed, the length of said

member being greater than the distance between the disc and closure, the distance between the shoulder and upper edge of the bottle neck being greater than the thickness of the disc to provide a space between the disc and the cap for the storage of a portion of said member, and said portion of said member being adapted to permit the disc to be removed without removing the closure.
